CLAIM

The ornamental design for a fly cutter cutting tool, as shown and described.

DESCRIPTION

FIG. 1 is a top perspective view of a first embodiment of my fly cutter cutting tool of my new invention with the mounting shaft welded to the cutting base and the carbide insert depicted in phantom;

FIG. 2 is a top plan view of my fly cutter cutting tool based on FIG. 1 and with the mounting shaft welded to the cutting base and the carbide insert depicted in phantom;

FIG. 3 is a front plan view of my fly cutter cutting tool based on FIG. 1 and with the mounting shaft welded to the cutting base and the carbide insert depicted in phantom;

FIG. 4 is a right plan view of my fly cutter cutting tool based on FIG. 1 and with the mounting shaft welded to the cutting base and the carbide insert depicted in phantom;

FIG. 5 is a rear plan view of my fly cutter cutting tool based on FIG. 1 and the reverse view of FIG. 3 and with the mounting shaft welded to the cutting base and with the carbide insert depicted in phantom;

FIG. 6 is a left plan view of my fly cutter cutting tool based on FIG. 1 and the reverse view of FIG. 4 and with the mounting shaft welded to the cutting base and the carbide insert depicted in phantom;

FIG. 7 is a bottom plan view of my fly cutter cutting tool based on FIG. 1 and the reverse view of FIG. 2 and with the carbide insert depicted in phantom;

FIG. 8 is a top perspective view of my fly cutter cutting tool based on FIG. 1 and with the mounting shaft welded to the cutting base;

FIG. 9 is a top perspective view of a second embodiment of my fly cutter cutting tool of my new invention with the mounting shaft and the cutting base as a unitary piece and with the carbide insert depicted in phantom;

FIG. 10 is a top plan view of my fly cutter cutting tool based on FIG. 9 and with the mounting shaft and the cutting base as a unitary piece and with the carbide insert depicted in phantom;

FIG. 11 is a front plan view of my fly cutter cutting tool based on FIG. 9 and with the mounting shaft and the cutting base as a unitary piece and with the carbide insert depicted in phantom;

FIG. 12 is a right plan view of my fly cutter cutting tool based on FIG. 9 and with the mounting shaft and the cutting base as a unitary piece and with the carbide insert depicted in phantom;

FIG. 13 is rear plan view of my fly cutter cutting tool based on FIG. 9 and the reverse view of FIG. 11 and with the mounting shaft and the cutting base as a unitary piece and with the carbide insert depicted in phantom;

FIG. 14 is a left plan view of my fly cutter cutting tool based on FIG. 9 and the reverse view of FIG. 12 and with the mounting shaft and the cutting base as a unitary piece and with the carbide insert depicted in phantom;

FIG. 15 is a bottom plan view of my fly cutter cutting tool based on FIG. 9 and the reverse view of FIG. 10 and with the carbide insert depicted in phantom; and,

FIG. 16 is a top perspective view of my fly cutter cutting tool based on FIG. 9 and with the mounting shaft and the cutting base as a unitary piece.
